UNITED STATES PATENT OFFICE

JOSEPH PAYTON COLLINS, OF BAKERSFIELD, CALIFORNIA

FLOW CONTROL APPARATUS FOR WELLS

Application filed January 19, 1931. Serial No. 509,801.

My invention relates to and has for a purpose the provision of an apparatus by which the flow of fluid from a gusher or "wild" well, can be readily brought under control and the 5 fluid held in check in such manner as to enable a control head or cap to be applied to the well casing with ease and dispatch.

It is a further purpose of my invention to provide an apparatus of the above described 10 character which embodies a carriage movable over the ground and supporting a plugging element capable of being readily lowered into the casing to gradually check and finally arrest the flow of fluid, and to be then 15 secured in the casing so that upon detaching the plugging element from the apparatus, the casing can be threaded if necessary and a control head or cap applied.

I will describe only one form of flow control 20 apparatus for wells embodying my invention, and will then point out the novel features thereof in claims.

In the accompanying drawings:

Figure 1 is a view showing in plan, one 25 form of flow control apparatus for wells embodying my invention.

Figure 2 is a view showing the apparatus of Figure 1 in side elevation.

Figure 3 is an enlarged vertical sectional 30 view taken on the line 3—3 of Figure 1 and looking in the direction of the arrows, and

Figures 4, 5, and 6 are sectional views taken 35 respectively on the lines 4—4, 5—5, and 6—6 of Figure 3 and looking in the directions of the respective arrows.

Referring specifically to the drawings in which similar reference characters designate similar parts in each of the several views, my invention in its present embodiment comprises a carriage C constructed of a pair of spaced apart and parallel longitudinal members 10 and 11, and a pair of spaced apart and parallel transverse members 12 and 13 arched longitudinally and secured in intersecting relation to the longitudinal members 40 by bolts 14 or other fastening means. The several members are preferably constructed of heavy metal such as discarded railroad rails so as to produce a carriage of sufficient 45 weight to prevent its being lifted from the

ground by the force of a column of fluid ejected from a well under tremendous natural pressure.

One end of each longitudinal member 10 and 11, is curved upwardly in the manner of a sled runner and is connected to a suitable hauling cable 15 which is adapted to be attached to a tractor or other hauling apparatus to drag the carriage over the ground. Other hauling cables 16 are connected to the longitudinal members for pulling the carriage laterally, and facilitate in positioning the carriage at a predetermined location with respect to the mouth of a well casing K.

Secured to the members 10, 11 and 12, and rising from the carriage intermediate its ends, are the legs 17 of a tripod T, the upper ends of the legs being secured to a sleeve 18 for co-action of the legs with a brace member 19 in rigidly supporting the sleeve vertically in a fixed and elevated position on the carriage.

The tripod and sleeve broadly constitute a means for mounting a closure or plugging element P on the carriage for movement vertically to occupy either the raised position 75 shown in full lines in Figure 2 wherein the element P is elevated from the ground, or the lowered position shown in Figure 3 and in broken lines in Figure 2, wherein the element is disposed in the casing K to plug the mouth of the latter against the escape of fluid from the casing.

The plugging element P is in the form of an elongated and conical body 20, the upper and larger end of which is provided axially with an externally threaded shank 21 which is detachably secured to a similar shank 22 on a feed screw 23 by means of a coupling collar 24. The feed screw 23 is freely received in the bore of the sleeve 18 and is restricted to longitudinal or vertical movement in the sleeve by means of radial lugs 25 on the screw which traverse longitudinally extending slots 26 formed at diametrically opposed points in the sleeve.

A nut in the form of a bevel gear 27 is threadedly mounted on the feed screw 23 and is confined within the opening 27a of a head 28 on the lower end of the sleeve 18, against displacement longitudinally of the screw so

that upon rotation of the gear in one direction or the other, the screw and hence the plugging element P will feed upwardly or downwardly.

5 A bevel pinion 29 is rotatably mounted on a stub shaft 30 secured in a boss 31 on the sleeve, and meshes with the gear 27, the pinion being retained against displacement axially of the shaft by means of a pin 32 extending through the hub of the pinion into an 10 annular groove 33 in the shaft.

15 A flexible shaft 34 which may extend any required distance from the carriage, is connected to the pinion 29 by a universal joint 35, and constitutes a means by which the pinion 29 can be rotated either manually or from a suitable source of power (not shown), to drive the gear 27 and hence feed the plugging element vertically as desired.

20 Slidable vertically in longitudinally extending dovetail grooves 36 formed at circumferentially spaced locations in the conical body 20 of the plugging element, are slips 37 having lugs 38 in which are journaled the reduced extensions 39 of feed shafts 40 threaded in the body as shown in Figure 3. In the present instance three slips are shown and are retained against axial displacement from the respective feed shafts 40 by nuts 41 on the extensions 39 of the shafts, to the 25 end that upon rotating the latter in one direction or the other, the slips will be moved longitudinally of the body to occupy either the contracted position shown in full lines in Figure 2, wherein the slips are disposed within the largest diameter of the body, or the expanded position shown in broken lines in this figure, wherein the slips project beyond the largest diameter of the body into engagement 30 with the inner wall of the casing K, to fixedly secure the plugging element in the casing against displacement under fluid pressure within the casing.

The feed shafts can be actuated by means 45 of a suitable tool such as a handled rod 42 of the required length capable of being extended into the casing to reach the plugging element P and terminating in a universal joint 43 one member of which has an angular 50 socket receiving the upper end of any one of the feed shafts 40 which projects from the body 20 and is of an angular form corresponding to that of the socket as indicated at 44.

55 The use and operation of the apparatus is as follows:

The apparatus with the plugging element P occupying the raised position shown in full lines in Figure 2 and with the slips 37 occupying the contracted positions shown in full lines in Figure 3, is drawn over the ground by the hauling cables to a position in which the plugging element is directly above the well casing K from which a column of 60 gas and/or oil is issuing.

The column of fluid in striking the inclined surfaces of the conical body 20 will naturally spread radially so that its action in tending to lift the apparatus from the ground will be reduced, although it is to be understood that the weight of the apparatus should be sufficient to resist the maximum force capable of being exerted upon the apparatus by a solid column of oil.

70 The plugging element is now fed downwardly by rotating the flexible shaft 34, until the element P enters the casing and occupies the position shown in broken lines in Figure 2 and in full lines in Figure 3. As the element enters the casing, it will be clear that due to the conical form of the body 20, the flow and velocity of the fluid will be smoothly and gradually checked. As the largest diameter of the body 20 is but slightly less than the internal diameter of the 75 casing, there will be very little escape of fluid around the element.

80 The slips 37 are now expanded by means of the handled rod 42, the socket of which is applied to the angular portions 44 of the feed shafts 40 and the latter rotated until the slips become tightly jammed against the inner wall of the casing to thus fixedly secure the plugging element in the casing against displacement by internal pressure. The 85 coupling collar 24 can now be unscrewed from the shank 21 of the body 20 to detach the plugging element from the feed screw 23 and thus permit the apparatus to be moved away from the casing and a cap or control 90 head to be applied to the casing as desired. As the plugging element is disposed wholly within the casing, threads can be readily cut upon the latter should this be necessary in order to apply a control head or cap to the 95 casing.

100 Although I have herein shown and described only one form of flow control apparatus for wells embodying my invention, it is to be understood that various changes and modifications may be made therein without departing from the spirit of the invention and the spirit and scope of the appended 105 claims.

110 I claim:

1. A flow control apparatus for wells comprising a carriage movable over the ground, a sleeve supported vertically on the carriage, a feed screw mounted in the sleeve for movement vertically and having a closure element for the well casing secured thereto, means for preventing rotation of the feed screw in the sleeve, a nut threadedly mounted on the feed screw and confined against movement 115 longitudinally of the screw, and means for rotating the nut to feed said screw in the sleeve and thereby raise or lower the closure element.

120 2. In a flow control apparatus for wells, a

plug adapted to be inserted into a well casting, slips mounted on the plug to occupy contracted and expanded positions, feed shafts in the plug connected to the slips to expand or contact the latter according as the shafts are rotated in one direction or the other, and means for rotating the feed shafts.
